UNITED STATES PATENT OFFICE.

GEORGE HENRY GLEDHILL, OF HALIFAX, ENGLAND, ASSIGNOR, BY MESNE ASSIGNMENTS, TO THE VICTOR CASH-REGISTER COMPANY, OF CHICAGO, ILLINOIS.

CASH-REGISTER.

SPECIFICATION forming part of Letters Patent No. 634,726, dated October 10, 1899.

Application filed April 6, 1898. Serial No. 676,678. (No model.)

To all whom it may concern:

Be it known that I, GEORGE HENRY GLEDHILL, a subject of the Queen of Great Britain, and a resident of Halifax, in the county of

5 York, England, have invented certain new and useful Improvements in Cash-Registers, of which the following is a specification.

My present invention relates to improvements upon the machine set forth in my application, Serial No. 664,057, filed December 28, 1897.

Referring to the accompanying drawings, Figure 1 is a view in side elevation of the cash-register mechanism provided with my improvements; Fig. 2, a broken perspective view showing the ratchet-pawl-locking detent device; Fig. 3, a view like that presented by Fig. 1, but showing the condition of the mechanism under depression of an operating-key; 20 Fig. 4, a broken perspective view of the pivotal stop-bar detail for the tablet-controlling levers; Fig. 5, a vertical sectional view taken through the mechanism along an operating-lever, with the parts in their normal relative 25 positions; and Fig. 6, a view like that presented by Fig. 5, but showing the condition of the mechanism under depression of an operating-key.

The case for inclosing the operating mechanism is not shown, but it may involve any convenient or suitable shape.

1 is the main drum or shaft, stationarily supported in a suitable frame 2 and carrying the series of rotatable register-wheels 3, each 35 provided with a circumferential series of ratchet-teeth 4 in desired number, according to the circumferential registering capacity of the wheel. At the front of the frame is supported stationarily a transverse shaft 5, 40 having pivotally mounted upon it a series of key-levers 6, one for each wheel, carrying at their outer ends buttons 7, each marked with a number denoting the value to be registered by operating the key. On each key-lever is 45 pivoted a pawl 8 to engage the ratchet-teeth of its register-wheel. The arrangement is such that by operating any key-lever its pawl will turn the respective wheel 3 through the space of one ratchet-tooth, and to prevent accidental movement of any wheel through 50

more than that space each key-lever may be provided with a brake-dog 9, which engages with a tooth on its ratchet-wheel at each operation.

I prefer to mark the key-lever at the extreme right-hand side of the machine with the lowest number to be registered—say “1”—the next “2,” the third “3,” the fourth and fifth “4” and “5,” respectively, and so on through the series, to represent, respectively, one cent, two cents, three cents, four cents, five cents, and so on. Each recording-wheel has marked upon its periphery a series of figures beginning at zero and continuing in a progression, having the number on its key-lever 55 as a multiplicator. Thus the wheel with which the one-cent key-lever gears is marked “0, 1, 2, 3, 4, 5,” and so on, and the wheel with which, say, the three-cent lever gears is marked “0, 3, 6, 9, 12, 15,” and so on. 60

Extending across the whole width of the bank of wheels 3 is an index-bar B, which allows only one number on each wheel to be seen, the arrangement being such that before any key-lever has been operated each wheel 75 will show zero, and on the first operation of a key-lever, say the ten-cent, the relative register-wheel will be turned by the means described through the space of one tooth, and “10” will be shown in the place of the zero, 80 while the second operation of said key-lever will cause “20” to be shown, and so on. 70

In order that a purchaser may know that the amount of his purchase has been correctly registered, I pivotally mount a series 85 of supplemental levers 11 on a common shaft 12, stationarily supported on the frame 2 in suitable position, preferably behind and below the bank of register-wheels. The inner end of each key-lever is adapted to engage 90 with the adjacent end of its relative lever 11, the opposite end of which is connected by a wire 13 with a suitably-mounted bell-crank lever 14, which carries a tablet 15, bearing a number corresponding to that on its actuating key-lever. The arrangement is such that by operating any key-lever 6 its relative tablet 15 is raised into view of the purchaser and is maintained in its display position, by the mechanism hereinafter described, until an- 95 100

other key-lever is operated, when the raised tablet drops out of view and another, bearing the number on such other key-lever, is exposed to view. For retaining any tablet in its raised position there is provided a rocking frame composed of two pendent parallel bars 16, connected at their lower ends by a rod 17, extending across the machine, the bars being pivotally hung on the frame 2 at 17', and the frame is controlled by a spring 18, connected with one bar for returning the frame to normal position.

20 is a lever common to all the key-levers. It is pivoted at 19 to the right-hand side of the frame 2. A link 20' is pivoted to the opposite side of the frame.

21 is a rod connecting the lever 20 and link 20' and extending underneath all the key-levers as a part of the lever 20.

20 The depression of any key or any number of keys simultaneously operates the lever 20.

The mechanism thus far described is substantially the same as is set forth in my aforesaid pending application. The bell shown at 25 C and the means for operating it require no particular description in the present case.

Near its inner end the lever 20 is provided with a head 22', containing a cam-slot 22. Pivoted on centers 23 at the opposite sides of 30 the frame is a stop-bar 24, shown as an angle-bar or trough-shaped, which extends across and in close proximity to the key-levers and carries a pin 25, which in normal position is within the cam-slot. To this pin is connected 35 at one end a spring 26, the other end of which is attached to an arm or projection 27 on the common lever 20. Slight depression of any one or more key-levers depresses the rod 21 and raises the inner end of the lever 20, and 40 such slight depression also raises the cam-head 22' until the pin 25 is clear of the cam-slot, when by means of the tension of the spring 26 the stop-bar is turned over all the unoperated key-levers, locking them until the 45 operated key has completed its stroke. Continued motion of the key brings the face 28 of the head 22' against the pin 25 to retain the bar 24 in locking position during further movement of the cam-slot. Each key-lever 50 has a notch 29, so that if any attempt be made to return the key to normal position after a partial depression the notch engages the top of the stop-bar 24 to prevent such return until after a complete stroke.

55 The lever 20 is connected, through an elongated slot 31' near its inner end, with a bell-crank 31, provided with a rack 32, the teeth of which are so timed that the first engages a pawl 33 immediately after the bar 24 has 60 passed over the unoperated key-levers. The function of this rack and pawl is to prevent the return of the lever 20 until it has completed its stroke to an extent to have caused a pawl 8 to produce a registration of one 65 tooth on the bank of registering-wheels. Immediately after registration the rack 32 passes and releases the pawl 33, which is thereupon

pulled to its normal position by the spring 34. On the return stroke of any key and the lever 20 the pawl 33 rides over the rack 32 in 70 the opposite direction, preventing reversal of the key until it has reached normal position and its pawl 8 has assumed engagement with the next tooth of its register-wheel ratchet.

The face 35 of the cam-slotted head 22' encounters the pin 25 of the stop-lever 24 in the descent of the inner end of the lever 20 and pushes the pin back into the cam-slot. The stop-lever is then clear of all the key-levers, thus allowing the operated key to fall to normal position.

36 is a lever fulcrumed on the shaft 5 and having one end 36' protruding at the front of the case (not shown) and the opposite end connected with a rod 37, which extends underneath the lower ends of the pawls 8.

It is necessary to enable the register-wheels to be set back to zero that the pawls shall be disengaged from the ratchets 4. To accomplish this, the operator presses down the end 90 36' of the lever 36, thereby forcing the rod 37 against the lower ends of the pawls 8 to turn them inward and the upper ends backward out of engagement with the ratchets. To prevent operation of any key or keys while the 95 pawls are thus out of engagement with the registering-wheel ratchets, I attach to one side of the frame a pivotal detent 38, having an inward-projecting arm 39 to be engaged by the rod 37. Movement of the rod 37 under depression of the lever 36 allows the detent 38 to fall by gravity to vertical position over the common lever 20 to stop it at the point x against rising. On releasing the lever 36 36' and when the pawls 8 have reengaged their 100 ratchets 4 the continued movement of the rod 37 carries the arm 39 to its normal position and retracts the detent out of engagement with the lever 20 into the position in which it is illustrated.

In practice it is found that a quick return of the rod 17 causes undue vibrations, which permit it to ride out of engagement with the tablet-levers 11 and the raised tablet to fall in consequence. To prevent this vibration, I 115 provide a lever 40, fulcrumed on the frame at 41 and having secured to it a spring 80, tensioned against a pin 81 on the frame 2, the spring tending to draw the lever 40 so that the notch 42 therein shall engage a pin 43, 120 projecting from a swinging bar 16. A swinging arm 44, which is fastened to the bell-crank 31, bears against and lifts the lever 40 in the rise of the inner end of the bar 20 until the notch 42 is disengaged from the pin 43. The 125 continued movement of the bell-crank 31 brings the arm 44 against a bearing 45 on the adjacent bar 16, and further movement of the bell-crank enables the arm 44 to force the bar 16, by engagement with the incline 46 on the bearing 45, until the rod 17 swings clear of all 130 uplifted tablet-levers 11, allowing them to fall to normal position and drop their tablets. When the arm 44 has reached the point 47 of

the face 46, it is released from engagement with the respective bar 16, thereby allowing the rod 17 to fly back under the tension of the spring 18 into engagement with the raised levers 11. Immediately the arm 16 has assumed its normal position the notch 42 in the locking-lever 40 again engages the pin 43, preventing any oscillation of the frame 16 and compelling the rod 17 to retain all upper lifted tablet-levers 11.

What I claim as new, and desire to secure by Letters Patent, is—

1. In a cash-register, the combination with the key-levers of a lever common thereto and provided with a cam-slotted head, a pivotal stop-bar supported to extend across the free ends of said key-levers and carrying a pin to enter the cam-slot and having a spring connection with said common lever, substantially as and for the purpose set forth.

2. In a cash-register, the combination with the key-levers of a lever 20 common thereto and provided with a head 22' containing a cam-slot 22, and having the faces 28 and 35, and a pivotal stop-bar 24 supported to engage the free notched ends of said key-levers and carrying a pin 25 normally within said cam-slot and having a spring connection with said common lever, substantially as and for the purpose set forth.

3. In a cash-register, the combination with the key-levers and tablets, of supplemental

levers 11 connected from one side of their fulcrum with said tablets, a swinging frame having a rod 17 to engage said supplemental levers at the opposite side of their fulcrum, a spring-controlled lever 40 containing a notch 42 engaging a pin 43 on said frame, a lever 20 common to all said key-levers, and connections between said common lever and spring-controlled lever for actuating said frame to release the supplemental levers from said rod by operating a key-lever, substantially as described.

4. In a cash-register, the combination with the key-levers and tablets, of supplemental levers 11 connected from one side of their fulcrum with said tablets, a swinging frame carrying a bearing 45 and having a rod 17 to engage said supplemental levers at the opposite side of their fulcrum, a spring-controlled lever 40 containing a notch 42 engaging a pin 43 on said frame, a lever 20 common to all said key-levers, and a bell-crank 31 connected with said common lever and carrying an arm 44 to engage said lever 40 and bearing, substantially as and for the purpose set forth.

In testimony whereof I have hereunto set my hand in the presence of two subscribing witnesses.

GEORGE HENRY GLEDHILL.
